UNITED STATES PATENT OFFICE.

REUBEN FELIX HOFFMAN, OF HAMILTON, OHIO.

RADIATOR COVER.

Application filed March 24, 1919. Serial No. 284,729.

To all whom it may concern:

Be it known that I, REUBEN FELIX HOFFMAN, a citizen of the United States, residing at Hamilton, in the county of Butler and State of Ohio, have invented certain new and useful Improvements in Radiator Covers, of which the following is a specification.

My invention pertains to motor vehicle and aeroplane radiator covers, and the objects of my improvement are to effectively provide means for regulating and maintaining the temperature of the radiator and the balance of a motor cooling system, at or near a predetermined point, which is best suited to operate an internal combustion engine efficiently, and prevent same from cooling rapidly when not in use.

Also to provide a radiator roll curtain that is simple and may be operated freely when subjected to various air pressures.

This invention with its objects so far explained is of novel construction, which is composed of a combination of parts arranged as described and illustrated in the accompanying specifications and drawings in which:—

Figure 1 is a side elevation of a water cooling radiator, illustrating the improved radiator cover and curtain in place.

Figure 2 is a front elevation view of a radiator with cover and curtain in place.

Figure 3 is a rear perspective view of the cover and curtain.

Figure 4 is a sectional perspective view of the rolled curtain.

Figure 5 is a perspective view of the curtain unrolled.

Figure 6 represents a plan view of a motor hood and radiator with cover in place, and showing operating arrangement for roll curtain.

Figure 7 is a sectional plan view of radiator cover on the line $b-b$, as shown in Figure 2.

Figure 8 is a plan of radiator cover only, showing circular opening 31 which fits around radiator filler tube.

Figure 9 is a transverse vertical section of radiator on line $a-a$, Figure 2.

Figure 10 is a front elevation view, illustrating details of curtain operation means and reinforcements.

Figure 11 is a side elevation view of pull

cord locking means which is located near operator's seat.

In referring to the different parts hereby shown, 14 indicates a radiator over which the cover 17 and 17^a is securely attached by means of cables or cords 9, 9 and 7, 7 which are maintained under a constant stress by the coil spring 8. Cables 9, 9 are attached with one end to one end of coil spring 8, and with the other end to wire reinforcement 10 by means of clasps 20, 20. Cables 7, 7 also are attached with one end to one end of coil spring 8 and extend therefrom and under radiator 14 with their other ends attached to bar 13 by means of clasps 6, 6. The combination of parts 8, 7, 7, and 9, 9, serve as means for maintaining a constant tension on cover 17 and thereby securely holding same in close contact with radiator.

Radiator cover 17 and 17^a is constructed of a flexible, fibrous material of sufficient thickness to effectively retard the radiation of heat therethrough. Cover 17 and 17^a is reinforced, at its rear edge, by wire 10 which extends along its entire edge and is securely attached thereto, and along the entire edge of front opening by bar 13, tubular housing 11, 11 and bar 41.

1 indicates a roll curtain which is made of a flexible, fibrous material similar to cover 17 and 17^a and of about the same thickness, and is secured to 17^a by means of clasps 23 and is so arranged to cover the entire front opening in cover 17^a when in an unrolled position. Roll curtain 1 is also constructed with two coil springs 15, 15 (see Figures 4 and 5) which extend along its entire outer edges and are securely attached thereto. Springs 15, 15 are so constructed that when they are in a released or normal state they will forcibly roll curtain 1 in a small compact roll (see Figure 4).

Operating cords 2, 2 are attached adjacent the ends of rod 18, and are rolled up with curtain 1 taking their position between the layers of same from where they extend upward and over pulleys 19, 19, then downward through tubular housings 11, 11 passing over pulleys 3, 3 and rearward through housing 28 to operating handle 27.

Operating cords 2, 2 cooperating with pulleys 19, 19, tubular housing 11, 11, pulley 3, 3, housings 4, 4, tubular housings 28, 28 and

locking device, as shown in Figure 11, with handle 27 serve as means for operating curtain 1 from the driver's seat. By pulling upward on handle 27 to a position at 27° the cord is released and the curtain can be raised or lowered, exposing any amount of cooling surface as desired, and the reaction of the coil springs 15, 15 exerts a constant tension on cords 2, 2 which tends to hold the curtain firm in and close contact with the radiator.

Pulleys 3, 3 are rotatively mounted in housings 4, 4 for the purpose of preventing wear and friction on cords 2, 2.

15 Housing 4 provides means for supporting pulley 3 and is attached to radiator support 36 or other suitable place below the radiator, and is connected with tubular housing 28 at its lower extension by means of threads, 20 and with the upper extension slidably connected to housings 11, 11. Openings closed by screw plugs 5 provide means for replacing cords 2, 2 when necessary.

25 Tubular housings 11 extend upward from housings 4, 4 to metal bar 41 where they are split, flattened and attached to bar 41 by means of rivets 22 or other suitable method, and serve as means for guiding cords 2, 2, reinforcing cover 17° and providing a surface for curtain 1 to roll upon.

30 Bar 41 extends across the upper edge of the opening in cover 17° and is securely attached thereto, by means of rivets or other suitable securing means and provides means for rotatively supporting pulleys 19, 19 in alignment with tubular housings 11, 11 and holding the cover in proper shape.

35 Tubular housings 28, 28 are attached with one end to housing 4, 4 and extends rearwardly through instrument board 29 or other suitable part of machine within the operator's reach where they are held in place by jaw 30 and bracket 24, providing a guide and protection for cords 2, 2.

40 Stationary jaw 30 works in cooperation with moveable jaw 25 which is rotatively mounted on bracket 24 and has an extending arm 25° which is provided with an eye or loop hole at its end through which cords 2, 2 pass.

45 The combination of parts 30, 24, 25 and 25° have for their object, means for releasing and locking cords 2, 2 at various points in relation to the movement of curtain 1 over front of radiator cover opening.

50 Pulley 26 is rotatively attached to handle 27 which provides means for attaching cords 2, 2 to handle 27 and serves as an equalizer by exerting an equal amount of tension on each of the cords 2, 2.

55 Bar 13 extends along the lower edge of front opening in cover 17° and is securely attached thereto, with each end attached to tubular housing 11, 11, providing means

for attaching curtain 1 at clasps 23 and cables, 7, 7 at clasps 6, 6.

The combination of metal parts 13, 11, 11 and 41 serve as a means to reinforce and support cover 17 and 17° in proper shape 70 and in contact with radiator 14.

Wire reinforcement 10 extends along the entire front edge of cover 17 and has for its purpose, means for attaching cables 9, 9 by means of clasps 20, 20 and tends to reinforce and hold cover 17 in proper shape and in close contact with radiator 14.

75 Cover 17° is also provided with a flap 40 which protects operating parts from the weather and from being conspicuous.

Wire cables 32, 32 are attached with one end to metal bar 41 and pass upward under cover 17 with their other ends attached to metal plate 33 which in turn is attached to wire 10. The combination of parts 32, 32 and 33 serve as means to support cover 17 in place on radiator 14.

80 In operation, handle 27 is pulled upward to position at 27°, which unlocks cords 2, 2, curtain 1 is then moved upward or downward in a vertical line, exposing or covering a variable amount of radiator cooling surface as the case may require to maintain the proper working temperature of cooling system and motor.

85 The curtain may be held stationary at any point between its two limits of movements or may be used to cover or blanket the entire opening at front of cover 17°.

90 During travel at high speed or against violent winds curtain 1 may be operated or adjusted without any noticeable resistance, as no part of curtain 1 slides over the surface of radiator 14.

95 This cover and curtain is easily attached or removed from the radiator and is in no way directly attached to same.

Having thus described my invention, what I claim as new and desire to secure by Letters Patent, is:

1. In a device of the character specified, the combination of a shield having a front opening, a frame secured to the edges of said shield surrounding said opening, flexible means for detachably securing said shield and frame upon a radiator, a self winding curtain having one end secured to said frame, means inherent in said curtain for maintaining the same normally wound, a cable having its ends secured to the opposite end of said curtain and normally wound therewith, and means upon said frame for guiding said cable; with means operated from the dashboard of a vehicle for creating a tension upon said cable to unwind said curtain and said cable, for closing said opening.

100 2. In a device of the character specified, the combination with a shield having a front

- opening, a frame secured to the edges of said shield surrounding said opening, means for detachably securing said shield and its frame upon a radiator, of a curtain having one end 5 secured to said frame, a bar secured to the opposite end of said curtain, winding members in said curtain disposed in its longitudinal direction to maintain the curtain normally wound, a cable having its extremities 10 secured to said curtain bar and normally wound with said curtain and having its remaining portion extending to the dashboard of a vehicle, means upon said shield frame cooperating with means upon the vehicle 15 frame and dashboard for guiding said cable, and coordinating and simultaneously operable equalizing and retention devices upon the dashboard for controlling said cable and curtain, whereby to effect varying degrees of 20 covering and uncovering of said shield opening by said curtain.
3. In a cover for radiators, the combination of a shield for embracing a radiator and formed with a filler plug opening and 25 a front opening, a reinforcing frame secured in the rear edges of said shield, a frame secured in the edges surrounding the front opening in said shield and provided with a curtain, a reinforcing plate secured to 30 the top of said rear frame at the rear of the plug opening, reinforcing members at each side of the plug opening and extending from said plate to the top of said front frame, and cords attached to the sides 35 of said rear frame, cords also attached to the lower bar of said front frame and extending rearwardly beneath the radiator; with a coil spring at the rear of the radiator having the adjacent ends of the pairs of cords at-
- tached to the respective ends thereof, whereby to flexibly and removably attach said shield to said radiator. 40
4. In a cover for radiators, the combination of a shield for embracing a radiator and formed with a filler plug opening and 45 a front opening, a rear frame for said shield, a front frame for said shield surrounding the front opening therein, a frame connecting the upper portions of said rear and said front frames and reinforcing said plug opening, means for flexibly and removably attaching said shield and its frames to the radiator, and a self-winding curtain and actuating members operatively mounted 50 upon said front frame, a portion of said actuating members being wound within said curtain; with means for exerting a tension on said actuating members for causing said curtain to unwind for closing the front opening in said shield. 55
5. In a curtain for radiators, the combination of a flexible curtain body adapted to have one end secured to a support, spring coiling means in said curtain body to wind the same along its transverse direction, tension members secured to the free end of said curtain body and wound therewith between its convolutions, means for tensioning said tension members to distend said curtain body; and means to release the tension to 60 cause said curtain body to automatically rewind with said tension members therewithin. 65

In testimony whereof I affix my signature in the presence of two witnesses.
